CALCULATING ATTACHMENT FOR TYPEWRITING-MACHINES.

1,358,263.

Specification of Letters Patent.

Patented Nov. 9, 1920.

Application filed October 17, 1917. Serial No. 197,045.

To all whom it may concern:

Be it known that I, FERDINAND J. TILLMAN, a citizen of the United States of America, a resident of the city of St. Louis, State of Missouri, have invented certain new and useful Improvements in Calculating Attachments for Typewriting-Machines, of which the following is a full, clear, and exact description, reference being had to the accompanying drawings, forming a part of this specification.

My invention relates to an attachment for co-operation with the numeral key levers of a typewriting machine, the present invention pertaining particularly to means by which sums written in different columns upon a sheet of paper in the carriage of a typewriting machine may be set up in a single accumulator, and further to means under the control of the accumulator operating mechanism for actuating connectors by which the typewriting machine numeral key levers are connected to the calculating mechanism.

Figure I is a side elevation, partly in vertical section, of a machine embodying my improvements.

Fig. II is a rear elevation of the machine shown in Fig. I.

Fig. III is an inverted plan, on a reduced scale, of the base supporting the calculating mechanism.

Fig. IV is a top plan, partly broken out, of the forward portion of the accumulator operating and shifting means, and its casing.

Fig. V is an enlarged plan of a portion of the mechanism directly operable by the platen carriage of the typewriting machine.

Fig. VI is a horizontal section taken on line VI—VI, Fig. II, with the parts beneath said lines in plan.

Fig. VII is a top plan, partly broken out, showing the means for actuating the connectors movable into and out of engagement with the numeral key levers of the typewriting machine.

In the drawings, A designates a typewriting machine having a platen carriage B provided with a toothed bar C movable to and fro with said carriage. Said toothed

bar is adapted to receive drivers 1 which may be adjusted to desired positions along the bar and serve as actuating members during the travel of the platen carriage.

D designates a base surmounted by a casing E within which calculating mechanism is located. Said base and casing are located beneath the typewriting machine A, and the calculating mechanism, operable through the medium of the numeral key levers of the typewriting machine, may be of any suitable description, such for example as that shown and described in Letters Patent of the United States No. 1,003,671, issued to me Sept. 19, 1911. No invention being herein claimed for the calculating mechanism, it is deemed sufficient, in so far as the present invention is concerned, to state that the calculating mechanism includes a master wheel shaft 2 operable by the calculating elements under the control of the numeral key levers of the typewriting machine and having slidably mounted thereon a master wheel 3, movable step by step from one to another of the denominational sections or total wheels of an accumulator 4 in response to the step by step movement of the typewriting machine platen carriage, to which the latter is shifted for the purpose of setting up in the accumulator the results of calculating operations carried out through the medium of the numeral key levers of the typewriting machine.

The master wheel 3 is splined to the master wheel shaft 2 and is provided with a grooved hub extension 5, see dotted lines Fig. IV, which receives the fork of a shifter arm 6 carried by a sleeve 7, slidably mounted upon a rod 8, arranged in suitable supports 9 and 10, and extending in a line parallel with the master wheel shaft 2.

The shifter arm 6 and the sleeve 7 by which it is carried constitute a carriage F through the medium of which the master wheel 3 may be shifted step by step from one to another of the transmission wheels in the accumulator 4 when said carriage is acted upon by operating mechanism to be hereinafter described. The master wheel carriage F is normally held adjacent to the

left hand side of the accumulator 4 by a retracting spring 11, see Fig. IV, connecting said carriage to a fixed member, for example, the support 9, and the master wheel 3 is, therefore, normally adjacent to the accumulator transmission wheel of the highest order.

12 designates a throw lever pivotally connected at 13 to the bottom of the base D, and extending from the rear end of said base to a point beneath the master wheel carriage F. The throw lever 12 has fixed to it at its forward end a vertical pin 14 which extends through a transverse slot d in the base D and engages the master wheel carriage F, thereby providing for movement of said carriage toward the right when the throw lever is actuated by means to be presently described. The forward arm of the throw lever 12 is supported by a rest bar 15 also secured to the bottom of the base D and spaced therefrom. On the rear arm of the throw lever 12 is an abutment 16 engaged by a cam lever 17 fixed to a vertical shaft 18 and held in engagement with the abutment 16 by a spring 19, said spring being secured at one end to said cam lever and having its other end attached to a stud on the base D, (see Fig. II.).

20 The vertical shaft 18 extends loosely through a post 20 mounted on the base D and has fixed to it at its upper end a lever arm 21 provided with a notch 22.

25 23 designates a bracket secured to the typewriting machine A, and serving as a support for an upper post 24 located in vertical alinement with the post 20. A vertical shaft 25 rotatably arranged in said upper post 24 has fixed to it at its lower end a lever arm 26, which carries a downwardly extending stem 27 for engagement with the lever arm 21 on the shaft 18. These parts 21 and 27 are maintained in engagement with each other due to the action of the spring 11 upon 30 the master wheel carriage F and the throw lever 12 which causes the shaft 18 to be so rotated as to hold the stem 27 in the notch 22 of the lever arm 21.

28 35 28 designates a crank arm fixed to the upper end of the vertical shaft 25, and 29 is a dog pivoted at 30 to said crank arm 28 and extending into the path of travel of one or more drivers 1 secured to the typewriting machine platen carriage C. The dog 29 is normally held by a spring 31 against a stop 32 carried by the crank arm 28. When the platen carriage is partaking of a step by step movement in the direction indicated by the arrow in Fig. V, the dog 29 rests against the stop 32 so that when said dog is engaged by a driver 1 the dog will act as an extension of the crank arm 28 with the result of causing rotation of the vertical shaft 25. After a driver 1 has passed out of engagement with 40 the dog 29, a spring 33, connected at one end

to the lever arm 26 on the shaft 25 and at its opposite end to a fixed pin 34 supported by the bracket 23, serves to return said shaft 25 to its normal position after it has been rotated through the medium of a driver 1 and the dog 29. When the platen carriage is drawn backwardly the spring 31 permits turning movement of the dog 29 on the pivotal point 30 and allows the driver 1 to pass. The spring 31 then returns the dog to its 45 normal position.

In the practical use of the mechanism herein described, the operation is as follows:

It will be assumed that an operator of the typewriting machine A desires to perform a 50 calculation involving two columns of figures written upon a sheet of paper in the platen carriage B of a typewriting machine, and to compute the items in both of said columns in the single accumulator 4. The operator 55 places two drivers 1 upon the typewriting machine platen carriage bar C, for example, in the spaced positions seen in Fig. II, and which correspond to the points at which the columns of the figures are to be written upon 60 a sheet of paper in the typewriting machine platen carriage. The operator having operated the typewriting machine to the point at which the first column of figures is to be entered upon the sheet of paper, a driver 1 65 will engage and press against the dog 29, and the latter will move the crank arm 28 in a circular path, thereby partially rotating the vertical shaft 25 and causing the lever arm 26 to move in a circular path and carry with 70 it the stem 27 in engagement with the lever arm 21 on the shaft 18. The shaft 18 during its rotation carries with it the cam lever 17 which, by pressing against the abutment 16 carried by the rear arm of the throw lever 75 12, causes the forward arm of said throw lever to be moved the proper distance during each step by step movement of the typewriting machine platen carriage to advance the master wheel carriage F along the rod 8 80 and bring the master wheel 3 into position for the operation of the accumulator section of the first highest order to be utilized.

As the driver 1 engages the dog 29 the calculating mechanism is brought into co-operation 85 with the numeral key levers of the typewriting machine as will be hereinafter described. So when the operator operates a numeral key in this column the master wheel will register the numeral in the corresponding section of the accumulator, and as the typewriting machine carriage advances a step the master wheel 3 will also advance a step to the next section in the accumulator. This operation is continued 90 during the setting up of a line of figures on the sheet of paper in the typewriting machine platen carriage.

When the line of figures has been written 95 upon the sheet of paper in the typewriting 100

machine platen carriage and set up in the accumulator, the dog 29 escapes from the driver 1 it has engaged and the mechanism herein described, including the master wheel carriage, is returned to normal position due in part to the action of the spring 11 and in part to the action of the spring 33. The typewriting machine platen carriage is then advanced to the point at which 10 the second column of figures is to be written upon the sheet of paper in the carriage, and the second driver 1 being located in correspondence to the location of this second column of figures, said second driver provides for a second actuation of the master 15 wheel carriage F, simultaneously with the operation of the typewriting machine platen carriage. Therefore, the sum written in the second column is set up in the accumulator 20 4. If the accumulator is one having mechanism operable either forwardly or reversely, the items in the second column may either be added to those in the first column or subtracted therefrom, and the result shown in 25 the accumulator. It will be apparent that if the accumulator is one having mechanism operable in one direction only the result accomplished would be one of addition only.

As previously mentioned, the dog 29 is 30 pivoted at 30 and held by a spring 31 against the stop 32 when it is to be engaged by the drivers 1. When it is desired to use the typewriting machine independently of the calculating mechanism, the dog 29 may 35 be moved out of the way of the driver 1. The spring 31 is attached to an arm extending laterally from one side of the dog 29, and when said dog is moved to the left from the position shown in Fig. V to a position 40 which will place it out of the path of travel of the drivers 1, the point of connection between the spring and the lateral extension of the dog is carried in an arc of a circle to a position beyond the axis of the dog 29, so that the pull upon said dog by the 45 spring 31 will serve to hold the dog in an inoperative position. The dog being held in this position, the platen carriage of the typewriting machine may move to and fro during the use of said machine for ordinary 50 writing, the said dog being returned to operative position only when calculations are to be performed.

It is desirable, in the use of a typewriting 55 machine for operating calculating mechanism, to provide means whereby the calculating mechanism may be disconnected from the numeral key levers of the typewriting machine so that said numeral key levers may be utilized during ordinary writing operations. In my earlier invention shown and described in Patent No. 1,003,671 hereinbefore mentioned, the disconnection of the calculating mechanism from the key levers is 60 accomplished through the medium of the

platen carriage of the typewriting machine, but according to my present invention such disconnection is performed by mechanism actuated by the master wheel carriage F, which controls the position of the master 70 wheel by which the accumulator elements are operated.

The calculating mechanism includes operating elements 35 (see Fig. I) to which are pivoted connectors 36 having upwardly extending members movable into and out of engagement with studs k on the numeral key levers K of the typewriting machine. The connectors also include downwardly extending tails 37 loosely arranged between a 75 pair of rods 38 carried by rocker arms 39 pivotally supported by a rock shaft 40. The rock shaft 40 and the rods 38 extend transversely of the calculating mechanism, and the rock shaft 40 has connected to it a pull 80 spring 41 which tends to rotate said shaft and so move the rods 38 as to cause them to act upon the tails of the connectors 36 to place said connectors in engagement with the connection elements k carried by the 85 numeral key levers K.

S designates a double armed shifter bar pivotally mounted, intermediate of its ends, upon a post 42. This shifter bar comprises an arm 43 which engages the rocker 39 and 90 an arm 44 engaged by the master wheel carriage F.

When the calculating mechanism with which my improvements are utilized is at rest, the master wheel carriage F occupies 100 a position immediately back of the left-hand end of the accumulator 4, as previously mentioned, being held in this position by the spring 11. The spring 11 is stronger than the spring 41 connected to the rock 105 shaft 40 of the rocker 39, and consequently holds the master wheel carriage in its left-hand position and exerts a force against the shifter bar S sufficiently great to overcome the tendency of the spring 41 to move the 110 rocker 39 forwardly. However, when the master wheel carriage F is moved toward the right, as herein previously explained, during calculating operations, the shifter bar is relieved of the holding influence of 115 offered by the spring 11 and the spring 41 acts to move the rocker 39 forwardly, with the result of actuating the connectors 36 so that they are placed in engagement with the connection elements k on the key levers K, 120 upon the occurrence of which engagement the calculating mechanism becomes operable by said key levers. Upon the return of the master wheel carriage F to its left hand position the connectors 36 are thrown to inoperative positions, due to the actuation of the shifter bar S by the master wheel carriage.

I claim:—

1. The combination with a typewriting 130

machine having key levers and a platen carriage and a calculating mechanism operable by said key levers including an accumulator and an accumulator operating element movable step by step along said accumulator, of a carriage with which said accumulator operating element is associated, a throw lever engaging said accumulator operating element carriage, and means operable by said 10 platen carriage for actuating said throw lever, said last named means including a shaft extending into proximity with said typewriting machine platen carriage, and a series of elements for operating said shaft located at intervals lengthwise of the platen carriage.

2. The combination with a typewriting machine having key levers and a platen carriage and a calculating mechanism operable by said key levers including an accumulator and an accumulator operating element movable step by step along said accumulator, of a carriage with which said accumulator operating element is associated, 20 a throw lever engaging said accumulator operating element carriage, and means operable by said platen carriage for actuating said throw lever, said last named means comprising a shaft extending into proximity with said typewriting machine platen carriage, a dog carried by said shaft and a series of elements located at intervals lengthwise of said carriage adapted to engage said dog to operate said shaft.

3. The combination with a typewriting machine having key levers and a platen carriage and a calculating mechanism operable by said key levers including an accumulator and an accumulator operating element movable step by step along said accumulator, of a carriage associated with said accumulator operating element, a spring controlled driving lever having engagement with said accumulator operating element carriage, and means operable by said typewriting machine platen carriage for operating said driving lever in opposition to the restraining influence of the spring by which it is controlled, said last named means including a lever arm having engagement with said driving lever and a series of elements carried by said platen carriage adapted to be brought into service at intervals during the movement of the platen carriage.

4. The combination with a typewriting machine having key levers and a platen carriage and a calculating mechanism operable by said key levers, including an accumulator and an accumulator operating element movable step by step along said accumulator, of a carriage associated with said accumulator operating element, a shaft adapted to be rotated by the typewriting machine platen carriage at intervals during its movement, a second shaft operable by said first

named shaft, a cam lever carried by said second shaft, and a throw lever operable by said cam lever having engagement with said accumulator operating element carriage, whereby said last named carriage has 70 a step by step movement imparted thereto during the movement of the typewriting machine platen carriage.

5. The combination with a platen carriage of a typewriting machine and a calculating mechanism adapted to be operated by the key levers of said typewriting machine, said calculating mechanism including an accumulator and an accumulator operating element, of a carriage by which said 75 accumulator operating element is moved step by step along said accumulator, a throw lever having engagement with said operating carriage, a shaft having a cam lever engaging said throw lever, a second shaft for imparting rotation to said first named shaft, a dog carried by said second shaft, and a series of elements for operating said dog located at intervals lengthwise of said platen carriage.

6. The combination with a typewriting machine having key levers and a platen carriage and calculating mechanism operable by said key levers, said calculating mechanism including an accumulator, a master wheel for operating said accumulator, and a carriage by which said master wheel is adjusted along said accumulator, of means for operating said last named carriage comprising a shaft extending into proximity with said platen carriage, a dog secured to said shaft adapted to be engaged and turned by said platen carriage to rotate said shaft, and a spring adapted to hold said dog in position to be engaged by the platen carriage 95 and also in a position in which it is out of the path of travel of said platen carriage.

7. In a calculating machine, the combination with an accumulator and an actuator therefor, one of which is movable step by 100 step to change their denominational relation, an oscillatory transmission arm having a pivotal extension through which the step by step movement is transmitted, and a traveling carriage provided with a traveling power transmission member from which the movement is transmitted to said oscillatory transmission arm, said pivotal extension being normally located in the path of said traveling power transmission member 115 so as to partake of movement of said carriage, and means for retaining said pivotal extension in an idle position beyond the path of said traveling power transmission member.

8. In a calculating machine, the combination of an accumulator and an actuator therefor, one of which is movable step by step to change their denominational relation, a traveling carriage provided with a 120 125 130

traveling power transmission member from which the step by step movement is transmitted, and an oscillatory transmission arm extending into the path of said traveling power transmission member, said transmission arm being provided with an extension positively driven in one direction to positively transmit the step by step movement, and said extension being free to yield idly 10 in the opposite direction.

9. The combination with a typewriting machine having digit keys and a platen carriage, of calculating mechanism comprising an accumulator provided with total wheels 15 and a traveling carriage movable step by step to provide for the transmission of movement to the different total wheels, accumulator operating means including devices whereby motion is transmitted from 20 said digit keys to actuate the total wheels, and feeding devices whereby motion is transmitted from said platen carriage to said traveling carriage so as to advance the latter step by step, said feeding devices comprising a traveling power transmission member carried by said platen carriage, a driven member through which movement is transmitted to said traveling carriage, and an abutment pivoted to one of said members 25 30 and extending into the path of the other member to provide for the transmission of movement to said driven member, the pivoted abutment being free to move idly in one direction so as to permit the platen carriage 35 to travel in one direction without transmitting movement to said driven member.

10. The combination with a typewriting machine having digit keys and a platen carriage, of calculating mechanism comprising an accumulator provided with total wheels 40 and a traveling carriage movable step by step to provide for the transmission of movement to the different total wheels, accumulator operating means including devices 45 whereby motion is transmitted from said digit keys to actuate the total wheels, and feeding devices whereby motion is transmitted from said platen carriage to said traveling carriage so as to advance the latter step by step, said feeding devices comprising a traveling power transmission member carried by said platen carriage, an oscillatory driven member through which movement is transmitted to said traveling carriage, an abutment finger pivoted to said 50 oscillatory driven member and extending into the path of said traveling power transmission member, the pivoted abutment finger being free to move idly in one direction 55 so as to permit the platen carriage to travel in one direction without actuating said driven member, and a restoring spring whereby said oscillatory driven member is yieldingly held in its normal position, said 60 pivoted abutment finger being located in 65

said path when the driven member occupies its normal position.

11. The combination with a typewriting machine having digit keys and a platen carriage, of calculating mechanism comprising an accumulator provided with total wheels and a traveling carriage movable step by step to provide for the transmission of movement to the different total wheels, accumulator operating means including devices whereby motion is transmitted from 70 said digit keys to actuate the total wheels, and feeding devices whereby motion is transmitted from said platen carriage to said traveling carriage so as to advance the 75 latter step by step, said feeding devices comprising a traveling power transmission member carried by said platen carriage, a driven member through which motion is transmitted to said traveling carriage, an intermediate member through which motion is transmitted from said traveling power transmission member to said driven member, said intermediate member being pivoted to said driven member and shiftable to an 80 inoperative position wherein it cannot transmit movement from said traveling power transmission member to said driven member, and means for retaining said intermediate member in its inoperative position. 85

12. The combination with a typewriting machine having digit keys and a platen carriage, of calculating mechanism comprising an accumulator provided with total wheels and a traveling carriage movable step by 100 step to provide for the transmission of movement to the different total wheels, accumulator operating means including devices whereby motion is transmitted from said digit keys to actuate the total wheels, 105 and feeding devices whereby motion is transmitted from said platen carriage to said traveling carriage so as to advance the latter step by step, said feeding devices comprising a traveling power transmission member carried by said platen carriage, a driven member through which motion is transmitted to said traveling carriage, an abutment pivoted to said driven member 110 and extending into the path of said traveling power transmission member to provide for the transmission of movement to said driven member, the pivoted abutment being movable on its axis to an inoperative position beyond said path, and means for retaining said pivoted abutment in its inoperative position. 115

13. The combination of a typewriting machine having key levers and a platen carriage movable step by step, and calculating mechanism operable by said key levers and including an accumulator and a master wheel for actuating said accumulator, a carriage for advancing said master wheel along the accumulator, a throw lever from which 120 125 130

movement is transmitted to the last mentioned carriage, and means for transmitting the step by step movement from said platen carriage to said throw lever, the last mentioned means comprising an oscillatory shaft through which the movement is transmitted and an arm fixed to said shaft and extended into the path of a portion of said platen carriage.

- 10 14. The combination of a typewriting machine having key levers, a traveling platen carriage and calculating mechanism operable by said key levers, said calculating mechanism including an accumulator and
15 an actuator therefor, one of which is movable step by step to change their denominational relation, an oscillatory arm through which the step by step movement is transmitted, said oscillatory arm being extended
20 into the path of said platen carriage, connectors through which movement is transmitted from said key levers to said actuator, said connectors being movable to and from their operative positions, and the last

mentioned movements being controlled from 25 said oscillatory arm.

15. The combination of a typewriting machine having key levers, a traveling platen carriage and calculating mechanism operable by said key levers, said calculating 20 mechanism including an accumulator and an actuator therefor, one of which is movable step by step to change their denominational relation, an oscillatory arm through which the step by step movement is trans- 35 mitted, said oscillatory arm being extended into the path of said platen carriage, connectors through which movement is transmitted from said key levers to said actuator, said connectors being provided with con- 40 necting hooks movable into and out of operative engagement with said key levers, and said connecting hooks being under the control of said oscillatory arm.

In testimony that I claim the foregoing I 45
hereunto affix my signature.

FERDINAND J. TILLMAN.
